UNITED STATES PATENT OFFICE.

FRED R. PATCH, OF PROCTOR, ASSIGNOR TO HIMSELF AND REDFIELD PROCTOR, OF CENTER RUTLAND, VERMONT.

PUMPING-MACHINE FOR STONE-SAWS.

SPECIFICATION forming part of Letters Patent No. 326,323, dated September 15, 1885.

Application filed March 31, 1885. (No model.)

To all whom it may concern:

Be it known that I, FRED R. PATCH, of Proctor, in the county of Rutland and State of Vermont, have invented a new and Improved 5 Pumping - Machine and Distributing Device for Stone-Sawing Machines, of which the following is a full, clear, and exact description.

My invention relates to improvements in pumping-machines principally designed to be 10 used in pumping a mixture of sand and water, and distributing the same, in connection with machines for sawing and finishing stone.

Heretofore in all the so-called "sand-pumping" machinery extra counter-shafts and driving-belts have been supplied to drive said 15 pumping machinery, thereby using more machinery and power. This class of pumping or elevating machines has been found to be objectionable in use for the reason that they 20 require a large outlay of power to drive the extra machinery before mentioned. The sand and water have also heretofore been distributed over the stone to be sawed from a distributing-board in a fixed position, whether the stone

25 was high or low. When the stone to be sawed is low in the gang, the sand and water falling from the distributing - board which has been fixed high enough to admit large blocks cause great trouble from spattering. It wastes the 30 sand and water, annoys the sawyer, and injures the sawing machinery. It also requires more power to raise the sand and water to this unnecessary height. Hence the importance of a movable distributing - board that can 35 readily be adjusted to any height of stone in the gang.

The object of my invention is to provide a 40 pump and distributing apparatus of such construction that the sand and water may be regulated according to the amount required, which varies as the number of saws in the sawing-machine is larger or smaller, and also by the adjustable distributing - board, which can be lowered in sawing low stone, and obviates the 45 necessity of raising the sand and water any higher than each stone requires, thereby in both of these ways economizing the power, and said pump deriving its motion directly from the sawing-machine, thereby dispensing with 50 all extra counter-shafts or other driving ma-

chinery used in other so-called "sand-pumping" machines.

Reference is to be had to the accompanying drawings, forming a part of this specification, in which similar letters of reference indicate 55 corresponding parts in all the figures.

Figure 1 is a side elevation of my improved pumping-machine and distributing device for stone-sawing machines. Fig. 2 is an enlarged side and sectional view of the pumping device. Fig. 3 is a top view of the same, parts 60 being broken out. Fig. 4 is a sectional view of the vertical spout and its feeding device. Fig. 5 is an enlarged side view of the devices 65 for raising and lowering the spout.

A represents a block of stone in position to be sawed. B represents the gang-frame. U' U' are blocks upon which the stone rests while being sawed. P P are posts, which support the overhead part of the sawing-machine and 70 guide the gang - frame B. T represents the gang-bed. O represents the floor. I is the gang-pitman connecting the crank - wheel L with the gang-frame B.

The pump consists of a vessel or compartment, W', provided at each end with an upwardly-projecting curved cylinder, w', in the top of which a flexible diaphragm, l, is securely clamped, which is connected by a connecting-rod, a, with a pin, a², passed through 75 a longitudinal slot, h, in one end of a rocking lever, g, pivoted on an upright frame, b, secured to the supply-tank Y², into which supply-tank fresh sand and water are conducted 80 through the spout x from the sand-box M. A flanged neck, n, projects from each cylinder w' into the compartment W', and is held in 85 place by a toggle-lever, m, in the cylinder w', and resting against a cross-piece, t, of the neck, thus preventing the neck from being 90 forced into the cylinder w'. The inner end of the neck n is beveled, and a valve, o, is hung on the same. From the tank Y² a flanged neck, n', projects into each cylinder w', which necks n' are held in place by a toggle-lever, 95 m', resting against the cross-pieces t' of the said necks n', and preventing the necks n' from being forced into the tank Y². The outer ends of the necks n' are beveled, and on the beveled ends valves o' are hinged, which open 100

into the cylinders w' . From the pivoted lever g a lever, W , projects upward, which is provided with a longitudinal slot through which a bolt passes, which also passes through a rod, K , connecting the said lever W with the pitman I . The pivots a^2 in the lever g are connected by the rods c with the opposite ends of a lever, d , pivoted by the pivot f in the frame b on the tank Y^2 . The material is discharged from the compartment W' through the pipe Y , fitting on the necks r in the top of the said compartment. p is a hand-hole in the top of the compartment W' , which is closed by a suitable valve. At U is a waste-outlet. The spout R runs from the gang-bed T to the receiving-tank Y^2 for the purpose of conducting the used sand back to the receiving-tank, and S is an outlet for conducting off the waste sand and water. C represents one end of a distributing-board, which may be of any desired pattern. $D D$ are the straps by which it is suspended above the stone, and G^2 is a small rope, one end of which is attached to one end of each of the straps D , and the other end is wound around a shaft, J , on which a grooved pulley, H , is keyed. V is a hand-rope, one end of which is wound on the rope-pulley H and the other end is secured to a cleat, V^2 , on one end of the posts P . G represents a small rope, one end of which is wound on the shaft J , and the other end is attached to the upper end of the vertical spout F , below which the funnel E is provided, into which the spout empties. The discharge-pipe Y , leading from the pump, empties into the vertical spout F .

The operation is as follows: The gang-frame is set in motion by means of the crank-shaft L and the pitman I . By means of the connecting-rod K the lever W and the cross-piece g are reciprocated, and thereby the flexible diaphragms l are raised and lowered alternately. The fresh-sand box M is filled with sand and a small stream of water is conducted into the upper corner of the said box and washes a quantity of sand through the spout x into the receiving-tank Y^2 . When the diaphragm at one end of the pump is raised, the mixture of sand and water is drawn from the tank into that cylinder w' of the pump, the valve o' being raised. Then as the corresponding diaphragm l is forced down the mixture of sand and water is forced from that cylinder w' into the compartment W' up through the pipe Y and into the discharge-pipe F' , from which it passes down through the funnel E and from the distributing-board C upon the stone which is being sawed. The sand and water then pass through the kerfs of the stone upon the gang-bed, and flow down through the spout R into

the receiving-tank Y^2 , and so on until the sand is worn out, when it passes off with the water by overflowing the receiving-tank Y^2 , and then passes off through the water-drain S . When it becomes necessary to stop the pump, the waste-valve is opened, thereby allowing all the sand and water remaining in the pump to flow out, whereby settling of the sand and clogging of the machinery is prevented.

The operation of the distributing-board is as follows: When the stone is in a position for being sawed, the board is let down nearly to the said stone by slackening the hand-rope at V^2 . The distributing-board is then close to the stone and the scattering of the sand and water upon the remaining parts of the machine is prevented. When it is necessary to take out the stone and refill the gang, the board is raised by pulling on the hand-rope V , which revolves the pulley H and winds the ropes G^2 and G upon the shaft J .

From the foregoing it will be understood that the operation of my pumping-machine is not dependent on any particular size or construction, for by placing the said pump above the pit it becomes a suction-pump and performs the work as well as in the position in which I have shown it placed in Fig. 1. Very little power is required to operate a pumping-machine constructed in accordance with my invention. Ample leverage is provided for working the rocker-arm and diaphragms, and they are thus rendered easy of operation. I do not limit myself to any particular construction of pump or location of same; neither do I limit myself to the particular connection with the gang herein shown and described.

Having thus described my invention, I claim as new and desire to secure by Letters Patent—

1. The combination, with a stone sawing gang, of a pump for raising sand and water and a rod for connection with and for operating the said pump from the gang or pitman, substantially as herein shown and described.

2. In a stone-sawing machine, the combination, with the adjustable distributing-board C , of the funnel E and the vertical tube F , connected with the supply-pipe, substantially as herein shown and described.

3. In a stone-sawing machine, the combination, with the adjustable distributing-board C and the funnel E , of the vertical tube F , emptying into said funnel, the rope G , suspending the said tube from the pulley-shaft J , the pulley H on the said shaft, and the rope G , substantially as herein shown and described.

FRED R. PATCH.
